UNITED STATES PATENT OFFICE.

JULIUS LINDAUER, OF PARIS, FRANCE.

CLASP FOR HOSE-SUPPORTERS.

SPECIFICATION forming part of Letters Patent No. 766,272, dated August 2, 1904.

Application filed March 30, 1904. Serial No. 200,837. (No model.)

To all whom it may concern:

Be it known that I, JULIUS LINDAUER, a subject of the German Emperor, and a resident of 42 Faubourg du Temple, Paris, in the Republic of France, have invented a certain new and Improved Button-Flap for Clasps of Hose-Supporters, of which the following is a specification.

The object of this invention is to provide a new construction of button-flap in which the metallic button, entirely covered by the tissue, conserves for its head a very graceful appearance, since the tissue is snugly fitted around it, while its plate is quite invisible and cannot touch the skin by any point. The tearing of the hose is thus avoided on account of the tissue which covers the metallic button. The possibility of being injured is also avoided, since all the parts of the button are hidden, and besides a very graceful device, which can be easily constructed, is provided for. Finally, the button is not bulky, which is an appreciable advantage in such an application.

In the annexed drawings, Figure 1 is a plan view of the ribbon or tape which serves to form the button-flap. Fig. 2 shows in plan and sectional views the special tubular ribbon adapted to cover the head of the metallic button. Figs. 3 and 4 show in longitudinal section and in plan view the single ribbon and the tubular ribbon connected together by the metallic button. Figs. 5 and 6 show in longitudinal section and in plan view the next stage of the manufacture, the head of the button being engaged in the buttonhole of the tubular ribbon. Fig. 7 is a perspective view of the next stage of the manufacture, showing the button-flap passed in the slide of the metallic eye. Figs. 8 and 9 show in longitudinal section and in plan view the complete clasp with its flap finished. Fig. 9 shows the clasp as it is used.

The new button-flap is formed of three parts—a first flat ribbon or tape *a*, of cotton or silk tissue, a second tubular ribbon *b* without any selvage, and a metallic button *c*, provided with a plate which is preferably round and formed of a male and female part inserted with force one into the other at the moment of the mounting, as is well known.

The ribbon or tape *a*, Fig. 1, is perforated at one of its ends with a small round hole 1, adapted for the passage of the tail of the button, and near its other end it has an oval buttonhole which is preferably provided for during the weaving of the ribbon. 55

The tubular ribbon *b*, Fig. 2, has at one of its ends a small hole 3, made throughout both thicknesses, adapted for the passage of the tail of the button, and has near its other end a buttonhole 4, provided for only on one of the thicknesses during the weaving and arranged lengthwise. 60

The end of the ribbon *a* having the hole 1 is placed above the end of tubular ribbon *b* having the hole 3, this latter having been flattened. The tail of the button is then inserted in the holes 1 and 3, and the male and female part of the button are then fixed together by pressure, which gives the whole shown in Figs. 3 and 4. The free end of the tubular ribbon is then tucked over the ribbon *a* and the head of the button *c* is engaged in the buttonhole 4 of said tubular ribbon, as shown in Figs. 5 and 6. The head of the button is thus covered only by one thickness of the tubular ribbon. The free end of the ribbon *a* is thereupon engaged in the slide of the metallic eye *d*, which may be of any suitable form. The ribbon is folded over itself, so as to cover the bottom of the plate of the button *c*, as can be seen in Fig. 7, and it is then tucked over the button, so that its buttonhole embraces the head and shank of the button *c*, which have already been covered by the tissue of the tubular ribbon, as already stated. The head of the button is then clearly detached with its rounded form, the tissue fitting quite snugly against same on account of the clamping action produced by the buttonhole 2. It is then only necessary to fasten together by one seam the free ends of the ribbons *a* and *b* and to connect them at the same time to the lower layers of the ribbon *a*. Before making this seam the end of the ribbon *a* is tucked over itself, so as not to have a rayed outward edge, as is customary in the ordinary seaming work. 85 90 95

It may be understood that the button covered as above stated will not be bulky, be- 100

cause the tubular ribbon which surrounds the head of said button can be made out of a tissue as thin as desired. Besides, said button can be of any color and, namely, of a different color than that of the ribbon *a*.

The total thickness of the flap illustrated in Fig. 8 of the drawings is much greater than what it is in reality. It has been shown thus only on account of the necessities of execution of the drawings.

In manufacturing the button-flap the two ends of the tubular ribbon can be free instead of one of them being fixed to the ribbon *a* at the moment the button is secured in place.

15 In this case each of these ends is fixed to the ribbon *a* by a seam.

Having now described my invention, what I claim as new, and desire to secure by Letters Patent, is—

20 An improved button-flap for clasps of hose-

supporters comprising a metallic button *c* with a base-plate in combination with a tubular ribbon *b*, said ribbon having a buttonhole in one of the thicknesses therein and into which engages the head of the button *c*, a single 25 ribbon *a* one of the ends of which carries the button *c* and the other end of which after having passed in the slide of the usual eye of the hose-supporter clasp is tucked over itself and over the button and is then fixed by a seam, 30 said ribbon *a* having a buttonhole therein and embracing the head of the button *c* over the tissue of the ribbon *b*, substantially as and for the purpose set forth.

In witness whereof I have hereunto set my 35 hand in presence of two witnesses.

JULIUS LINDAUER.
